FOLDING TABLE

Thomas C. Dukes, Parnell, Mo.

Application July 30, 1936, Serial No. 93,470
Renewed December 3, 1937

3 Claims. (Cl. 311—62)

The present invention relates to new and useful improvements in tables and has for its primary object to provide, in a manner as hereinafter set forth, a table embodying a novel construction, combination and arrangement of parts through the medium of which said table may be expeditiously folded or unfolded as desired and which, when folded, will occupy a minimum of space.

10 Other objects of the invention are to provide a folding or collapsible table of the character described which will be comparatively simple in construction, strong, durable, highly efficient and reliable in use, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a bottom plan view, showing the table in open or extended position, the supporting legs being illustrated in horizontal section.

Figure 2 is a view in vertical section through the invention, taken substantially on the line 2—2 of Figure 1.

30 Figure 3 is a vertical sectional view taken substantially on the line 3—3 of Figure 1 looking in the direction indicated by the arrows.

Figure 4 is a bottom plan view, showing the table in folded position, the supporting legs being in horizontal section.

Figure 5 is a vertical sectional view, taken substantially on the line 5—5 of Figure 4.

Figure 6 is a view in bottom plan of a portion of the table top, showing the same in extended or unfolded position.

Figure 7 is a bottom plan view with the parts in an intermediate position of folding.

Figure 8 is a detail view in vertical section through a corner portion of the invention, taken substantially on the line 8—8 of Figure 3.

Referring now to the drawings in detail, it will be seen that the embodiment of the invention which has been illustrated comprises a pair of end sections which are designated generally by the reference numeral 1. The end sections 1 are adapted to be moved toward and away from each other and each of said end sections includes a pair of supporting legs 2 between which a rail 3 extends.

55 The movable end sections 1 are connected by

foldable rails which are designated generally by the reference numeral 4. The foldable rails 4 comprise comparatively short stationary end sections 5 which are fixed on the upper portions of the legs 2 and on which swinging sections 6 are hingedly mounted, as at 7. The sections 6 of the foldable rails 4 are adapted to swing inwardly and said sections 6 are connected at their inner ends by hinges 8.

Mounted on the folding rails 4 is a stationary 10 intermediate leaf 9. Hingedly mounted on the stationary intermediate leaf 9 are drop leaves 10 which are adapted to be supported in horizontal or operative position by the end sections 1, as shown to advantage in Figure 2 of the 15 drawings.

Referring now to Figures 6 and 7 of the drawings, it will be seen that substantially T-shaped grooves 11 and 12 are formed in the lower faces of the leaves 9 and 10, which grooves are aligned when the leaves 10 are in raised position. Extending inwardly from the grooves 11 in the stationary intermediate leaf 9 are oppositely curved substantially T-shaped grooves 13 which merge at their outer ends where they communicate with the grooves 11. An arcuate groove 14 connects the inner ends of the grooves 13. It will be observed that in the embodiment shown the grooves 11 to 14, inclusive, are formed by channelling leaves 9 and 10 and then securing over the channels countersunk metallic plates which are constructed and arranged to define comparatively narrow slots. Headed screws 15 are mounted in the upper ends of the legs 2 and on the rail sections 5 and said headed screws 30 are slidable in the grooves 11 and 12. The hinges 8 comprise pins 16 having heads 16' on their upper ends which are adapted to travel in the grooves 13 and 14.

Flexible cables or the like 17 extend slidably 40 through openings or notches which are provided therefor in the rails 3 and are provided on their outer ends with handles 18. The cables 17 are connected by branches 19 with the hingedly connected inner ends of the foldable rail sections 45 6, guides 20 being provided beneath the stationary intermediate leaf 9 for said cables and the branches.

It is thought that the operation of the invention will be readily apparent from a consideration 50 of the foregoing. With the end sections 1 in fully extended position, as seen in Figures 1 and 2 of the drawings, the hinged drop leaves 10 are supported in raised or operative position thereby. When it is desired to fold or collapse the table, 55

as seen in Figures 4 and 5 of the drawings, one of the cables 17 is pulled outwardly. This causes the hingedly connected rail sections 6 to swing inwardly on their hinges 7, the pins 16 of the 5 hinges 8 traveling in an arc in one of the grooves 13 until the inner end thereof is reached. This operation causes the end section 1 which is opposite the cable 17 which has been pulled to move inwardly beneath one side of the stationary intermediate leaf 9. Then, the other of the cables 10 17 is pulled outwardly in a manner to swing the hingedly connected inner ends of the rail sections 6 to the position shown in Figure 4 of the drawings, the pins 16 of the hinges 8 traveling in the 15 grooves 14. This last operation causes the other end section 1 to be drawn inwardly beneath the other side portion of the stationary intermediate leaf 9. When the end sections 1 are thus drawn inwardly beneath the leaf 9 the hinged leaves 10 20 are free to drop to folded position, as seen in Figure 5 of the drawings.

It is believed that the many advantages of a folding table constructed in accordance with the present invention will be readily understood, and 25 although a preferred embodiment of the device is as illustrated and described, it is to be understood that changes in the details of construction and in the combination and arrangement of parts may be resorted to which will fall within the scope of 30 the invention as claimed.

What is claimed is:—

1. A folding table comprising a pair of end sections movable toward and away from each other, said end sections including supporting 35 other, said end sections including supporting legs, foldable rails connecting the end sections, said foldable rails including inwardly swinging sections hingedly connected at one end, a stationary leaf mounted on the foldable rails, means slidably connecting the hingedly connected ends 40 of the foldable rail sections to said stationary leaf, a pair of drop leaves hingedly mounted on the stationary leaf, means slidably connecting

the end sections to the stationary and drop leaves, and means for actuating the rails to folded position for moving the end sections inwardly beneath the stationary leaf.

2. A folding table comprising a pair of end sections movable toward and away from each other, foldable rails connecting said end sections, said foldable rails including inwardly swinging sections hingedly connected at one end, a stationary leaf mounted on the foldable rails, drop leaves hingedly mounted on the stationary leaf and engageable for support on the end sections when said end sections are in extended position, the leaves having grooves therein aligned with each other when the drop leaves are in raised 15 position, the stationary leaf further having a curved groove therein communicating with the first-named groove at one end and still further having another groove therein communicating with the second-named groove at its other end, 20 means operable in the second and third-named grooves for slidably connecting the hingedly connected ends of the foldable rail sections to the stationary leaf, and means on the end sections operable in the first-named grooves for slidably 25 connecting said end sections to the stationary and drop leaves.

3. A folding table of the class described comprising a pair of end sections movable toward and away from each other, foldable rails connecting said end sections, a stationary leaf mounted on said foldable rails, the foldable rails including inwardly swinging sections hingedly connected at one end, means for slidably connecting the hingedly connected ends of 35 the swinging rail sections to the leaf, a pair of drop leaves hingedly mounted on the stationary leaf, cables for swinging the rail sections inwardly, and means slidably connecting the end sections of the table to the stationary and the drop 40 leaves.

THOMAS C. DUKES.
